SEALED PACKAGE AND CLOSURE
THEREFOR

Floyd R. Perkins, Chicago, Ill.

Application July 1, 1937, Serial No. 151,343

7 Claims. (Cl. 221—11)

This invention has to do with a sealed package for merchandise and the like, and relates more particularly to an improved package cover seal easily applied and removed.

5 The present day hermetically closed packages, which contain perishable goods such as coffee, fruits and sauces for household consumption, are customarily made of sheet metal or vitreous materials. Sheet metal containers are most commonly made air-tight by a line of solder holding the cover in place, while the same objective is usually accomplished in the case of vitreous containers by means of sealing wax in place of the solder, or, by the use of gasket clamped between the cover and the container proper. While these containers satisfactorily preserve their contents, they are costly and have the decided disadvantage of being difficult to open. Various kinds of cap and cover opening tools have 20 been devised with the view of alleviating the task of opening such packages, and in certain instances sheet metal containers have been provided with a specially constructed section adapted to be torn away by means of an accompanying tool.

The primary object of the present invention is the provision of a new container sealing means which may be easily removed for permitting access to the container contents without the use 30 of tools.

More specifically, the present invention contemplates in the hermetically sealed package art the use of a permanently tacky sealing member for holding the package cover in place.

35 Other desirable objects of the present invention will become apparent upon reading the following description with reference to the accompanying single sheet of drawing hereby made a part of this specification, and wherein:

40 Fig. 1 is an end view of a container having a closure embodying the principles of the present invention;

Figs. 2 and 3 are fragmentary cross-sectional views taken, respectively, upon the lines 2—2 and 45 3—3 of Fig. 1; and

Fig. 4 is a fragmentary cross-sectional view taken through the container shown in Fig. 1, substantially upon the line 2—2, and illustrating such container with its discharge spout in the 50 opened position.

Similar parts where shown and designated in several figures of the drawing and where referred to hereinafter will be indicated by the same reference character.

55 Attention is first directed to Figs. 1 and 4

where there is shown a sheet metal package or container having a cylindrical side wall 10 provided with a turned-over flange 11 about its upper edge. An end wall 12 has a peripheral flange 13 extending axially of the container and joined to the flange 11 by means of a line of solder indicated at 14. The connection between the end wall 12 and the side wall 10 is illustrative only. Any standard method of securing together the container walls may be employed. A discharge opening 15 is provided within the end wall 12. Such discharge opening 15 is closed by means of a spout closure member generally designated 16.

Upon opposite sides of the opening 15 there are 15 strap-like saddles 17 which receive opposite end portions of a pivot pin 18. One end of the spout 16 is curled at 19 about the mid-section of the pivot pin 18. An extended section 20 of the spout 16 is adapted to abut against an inwardly 20 turned lip 21 disposed at one end of the opening 15. Said spout 16 has two similar and opposed side walls 22, each of which has an abutment lug 23 thereon. That portion constituting the bottom of the spout when the spout is opened 25 for use as such has been designated 24, and forms the cover for the opening 15 when the spout is retracted into the container. The pin 18 and the lip 21 are so disposed inwardly of the container that the spout wall 24, when the spout is re- 30 tracted, lies flush with the outer surface of the end wall 12. Said spout wall 24 may be referred to particularly as a shock-absorbing member.

Above the shock-absorbing member 24 is a patch 25 comprising a fabric piece 26 coated on 35 its under side with a layer 27 of a permanently tacky substance. Such tacky layer 27 effects an adhesive connection between the fabric piece 26 and the shock-absorbing member 24, and, since the patch is of greater area than the discharge 40 opening 15, the tacky layer thereof adhesively engages the end wall 12 at a section immediately about the opening. The patch 25 may be obtained by cutting a section of the desired size 45 and shape from a larger piece of stock similar to that used for making masking tape or the like. There is no intention to limit the invention to any particular type of adhesively coated fabric for use in a sealed device of the present kind. 50 Adhesively coated fabrics of several manufacturers have been found to have the desired characteristics of resisting heat and moisture as make them well adaptable for use upon packages containing liquids, and packages which are sub- 55

jected to heat at the time they are filled or subsequently.

As an expedient to the preparation and filling of a package of the kind herein disclosed, the closure member 16 and the patch 25 may be applied while the opposite end of the package is open. The package may be filled through such opposite open end which will be permanently closed subsequently to that operation. This procedure of assembling and filling the package will insure the absence of spilled contents upon the exterior marginal edge of the opening 15 whereby such edge section will be clean at the time of applying the patch 25 and thus insure an effective adhesive connection thereto of the tacky material 21.

Experiments have shown that a seal of the kind here shown is effective for the preservation of subatmospheric pressure within the container and is further effective for retaining within the container liquid substances irrespective of the position of the container; that is, the container may be allowed to remain inverted with safety. The shock-absorbing member 24 receives the force which may be imparted by the container contents to the patch 25 because of the container being shaken or inverted. Such force is transmitted uniformly by the shock-absorbing member 24 to the patch 25. The shock-absorbing member 24 thus avoids the concentration of force upon any limited area of the adhesive connection between the patch and the container end wall 12, thereby preventing the breakage of the connection because of momentive force of the container contents in the event of such container being accidentally dropped or otherwise vigorously shaken. When the pressure within the package is lower than the ambient atmospheric pressure the latter pressure will augment the effect of the adhesive layer 27 to maintain the sealed joint between the closure member 24 and the container end wall 12. Also the constant inward pressure of the atmosphere upon the closure member will counteract any force imparted to such member by the container contents. Any likelihood of loosening the patch or sealing member 25 by scuffing against exterior objects may be diminished by recessing the end wall at the section containing the discharge opening 15, and by seating the member 25 in such recess.

Although the patch 25 avoids accidental displacement from the effect of force imparted thereto by the container contents, it is a relatively easy matter to remove such patch when desired. Removal of the patch may be accomplished by grasping an edge thereof between the thumb and forefinger and by lifting such edge whereby to strip the member from the container. The removal force is thus concentrated, making it easy to successively lift adjacent sections of the adhesive layer from the container end wall. The container is shown in Fig. 4 with the sealing member 25 removed and with the spout 16 in its distended position determined by the lugs 23 as they strike the depressed section of the end wall.

While only a single structural embodiment has been shown in this specification, manifestly, the invention will extend to many other forms, and so it is intended the scope of this invention shall be in nowise limited excepting as defined in the appended claims.

I claim:

1. In a hermetically sealed container enclosing a space of subatmospheric pressure, comprising a metal wall provided with an opening and subject to expansion and contraction with fluctuations in temperature, a shock-absorbing member removable in such opening, and a peelable sealing member having a permanently tacky adhesive surface extending beyond the limits of such opening, such surface being adhesively joined to said shock-absorbing member and to the section of said wall circumscribing the wall opening. 10

2. In a hermetically sealed container comprising a metal wall provided with a discharge opening and subject to expansion and contraction with fluctuations in temperature, a stiff shock-absorber member substantially congruent with the outline of such opening, and a flexible peelable sealing member having a permanently tacky surface, said shock-absorbing member being adhesively joined with a central portion of the 20 tacky surface of said sealing member thereby leaving a marginal edge portion of such surface extending beyond said shock-absorbing member, and said sealing member being disposed with such marginal edge adhesively engaged with said 25 container wall about the wall opening while floatingly retaining said shock-absorbing member within the wall opening.

3. A hermetically closed container comprising a metal wall having an opening and subject to 30 expansion and contraction with fluctuations in temperature, a discharge spout retractable through such opening into said container, said spout having a portion disposed substantially within the plane of said wall and providing a 35 floating closure for the wall opening while the spout is retracted, and a sealing member having a permanently tacky surface, said sealing member being of greater area than the container opening and being disposed over such opening 40 for retaining said spout in its retracted position, and the tacky surface of said sealing member being adhesively joined with the closure portion of said spout and with the container wall immediately about such opening.

4. A hermetically closed container comprising 45 a metal wall having a recess and an opening within the bottom of such recess, a shock-absorbing member disposed within such opening and substantially conforming thereto in shape, and a sealing member disposed within said recess, said 50 sealing member having a permanently tacky surface adhesively engaged with the bottom of said recess and with said shock-absorbing member, and said sealing member being of such thickness as to be substantially flush with the 55 surface of the wall at the brim of such recess.

5. A sealed container enclosing a space of subatmospheric pressure, a wall of said container being provided with an opening, a removable plate closing said opening, a sealing member comprising a fabric patch covering said plate and adjoining areas of said wall, said patch having its contacting side secured to said plate and wall areas by a layer of permanently tacky adhesive 60 to permit expansion and contraction of said wall 65 without loosening said patch.

6. The combination of claim 5 in which the plate is hinged to said wall.

7. The combination of claim 5 in which the plate is the base portion of a spout which is 70 hinged to said wall.

FLOYD R. PERKINS.
